UNITED STATES PATENT OFFICE.

FERNANDO CASABLANCAS, OF SABADELL, SPAIN.

SPINNING-FRAME.

1,092,631.

Specification of Letters Patent.

Patented Apr. 7, 1914.

Application filed May 25, 1912. Serial No. 699,750.

To all whom it may concern:

Be it known that I, FERNANDO CASA-
BLANCAS, a subject of the King of Spain,
residing at Sabadell, Barcelona, Spain,
5 have invented certain new and useful Im-
provements in Spinning-Frames; and I do
hereby declare the following to be a full,
clear, and exact description of the invention,
such as will enable others skilled in the art
10 to which it appertains to make and use the
same.

My invention relates to spinning frames
and consists in the constructions, arrange-
ments and combinations of parts herein-
15 after described and claimed.

It is an object of my invention to pro-
vide a spinning frame for drawing fibers
of different lengths and conducting the
same into close proximity to the drawing
20 rollers whereby the drawing is effected over
a relatively small length of the roving.

Another object of my invention is to pro-
vide a spinning frame adapted to short
length fibers and to maintain the latter un-
25 der pressure throughout their length and
to provide for adjusting the pressure means
to accommodate fibers of varying length.

In describing my invention in detail ref-
erence will be had to the accompanying
30 drawing, wherein like symbols refer to like
or corresponding parts throughout the sev-
eral views, and in which:—

Figure 1 is a vertical sectional view of
my improved spinning frame. Fig. 2 is a
35 similar view disclosing a slight modifica-
tion. Fig. 3 is a detail. Fig. 4 is a detail
of a slight modification, and Fig. 5 is an end
view of a different form of spinning frame.

Referring more particularly to Figs. 1 to
40 4 of the drawings, 1 and 2 designate a pair
of endless belts running over, respectively,
pairs of rollers 4 and 5 suitably mounted
on the framework. The rollers 4 are en-
larged and constitute the feeding rollers for
45 receiving the roving, while the rollers 5 are
relatively small so as to enable the same to
be located in close proximity to the drawing
rollers 3, which, as usual, run at rela-
tively higher speeds and pass the attenuated
50 fibers to the bobbin as shown and as will be
understood. A tension roller 6 adjustably
secured to the frame, as shown, provides
for taking up slack in the belt 2, and a
weight-controlled tension roller 7 bears
55 against both belts at a point intermediate

the rollers 4 and 5, and in addition to com-
pensating for the slack imparts the initial
pressure to the roving 11 which is fed be-
tween the rollers 4 and conducted by the
belts 1 and 2 to the rollers 5. Between the
tension roller 7 and the pair of rollers 5 is
60 located a convex plate 9 so supported from
the frame as to elevate the belts vertically
from the tension roller 7 and provide for a
substantially uniform pressure exerted
65 over approximately the entire length of the
fibers treated. This plate 9 extends in close
proximity to the rollers 5 and supports the
fibers as they are being drawn, thereby pre-
venting any creeping of the same and ob-
70 viating entanglement.

In place of the plate 9 I may employ a
segmental support 12, as shown in Fig. 2,
carrying a plurality of rods or rollers 13
preferably spaced apart in parallel relation.
75 While this construction does not yield as
perfect and continuous a pressure as that
disclosed in Fig. 1, yet, especially in the case
where rollers are used, the wear on the belt
2 is reduced and the resistance lessened so
80 as to be an economy as regards the motive
power.

Figs. 3 and 4 show details of the bearings
of the rollers 5 and means associated there-
with to supply the proper tension. In Fig.
85 3 the lower roller is journaled in a fixed
bearing, while the upper roller is mounted
in a rocking bearing 25 oscillating about a
pivot 26 and having a rearwardly-extend-
ing arm through which a set screw 28
90 loosely passes and is threaded into the
frame to regulate the required tension. A
coil spring 27 encircles the set screw 28 and
is adapted to maintain the arm normally in
contact with the screw head.

Fig. 4 discloses a bearing block 31 accom-
modating both journals of the roller 5 and
a flat spring 29 secured at one end to the
bearing block and having its free end en-
gaging against the upper roller journal. A
100 set screw 30 is arranged intermediate the
ends of the spring 29 and regulates the ten-
sion as will be understood.

In Fig. 5 I have illustrated a form of my
invention in which I dispense with one of
105 the endless belts 1, together with its neces-
sary parts, and supply in place thereof a
pressure plate 15. The plate 15 is remov-
ably carried by a frame 18 in which is jour-
naled a pair of rollers 19 and 20, over
110

which is trained the endless belt 2. The rollers 19 and 20 constitute the feeding rollers and receive the roving 11.

In order to accommodate fibers of different lengths the frame 18 carrying the feed rollers is adjustable so as to vary the distance between the latter and the drawing rollers, and for this purpose the frame 18 is mounted in a slotted bracket 16 and provided with a set nut for maintaining the frame in any adjusted position. After the frame 18 has been adjusted, as required, a plate 15 of a length to correspond approximately to the average length of the fibers treated is put in place and the operation proceeded with. The plate 15 extends down to a position over the roller 5 and has its end preferably beveled so as not to come in contact with the upper drawing roller 3 while being permitted to occupy a position in close proximity thereto.

I have shown and described preferred and satisfactory constructions, but desire it to be understood that slight changes may be resorted to without departing from the spirit and scope of my invention, provided such changes fall within the scope of the appended claims.

I claim:

30 1. In a spinning frame, a pair of drawing rollers, a pair of feeding rollers, a movable frame carrying said feeding rollers and adapted to be adjusted to vary the distance between said drawing and feeding rollers, an endless belt trained over said feeding

rollers for conducting the fibers in proximity to the drawing rollers, and a plate removably carried by said frame and of a length to correspond approximately to the adjusted distance between said drawing and feeding rollers, said plate being adapted to exert a substantially uniform pressure upon the fibers.

2. In a spinning frame, a pair of drawing rollers, an endless belt for conducting the fibers to said drawing rollers, a pair of movable rollers over which said belt is trained and adapted to receive the fibers, and a plate of a length corresponding to the average length of the fibers being treated extending between said movable rollers and the drawing rollers and exerting a substantially uniform pressure upon the fibers.

3. In a spinning frame, a pair of drawing rollers, a pair of feeding rollers adjustable with respect to said drawing rollers to accommodate fibers of different length, an endless belt trained over said feeding rollers for conducting the fibers in proximity to the drawing rollers, and a plate of a length to correspond to the average length of the fibers extending between said movable rollers and the drawing rollers and exerting a substantially uniform pressure upon the fibers.

In testimony whereof, I affix my signature, in presence of two witnesses.

FERNANDO CASABLANCAS.
